Primary Examiner — Eric Goodman*Assistant Examiner* — Clesse Moore, Jr.(74) *Attorney, Agent, or Firm* — Brian J. Colandreo, Esq.; Jeffrey T. Placker, Esq.; Holland & Knight LLP**CLAIM**

The ornamental design for a dosing cup, as shown and described.

DESCRIPTION

FIG. 1 is a perspective view of the new design applied for the dosing cup in accordance to the present industrial design.

FIG. 2 is a side view thereof;

FIG. 3 is a front view thereof, which is equivalent to the rear image thereof;

FIG. 4 is another side view thereof;

FIG. 5 is a top view thereof; and,

FIG. 6 is a bottom view thereof.

The broken lines are included for the purpose of illustrating portions of the dosing cup that form no part of the claimed design.
